COMPOUND LUG WRENCH TOOL

Robert V. Broughton, R.D. 2, Crane Road,
Horseheads, N.Y. 14845

Filed Jan. 5, 1968, Ser. No. 10,065

Term of patent 14 years

U.S. Cl. D54—13
Int. Cl. D8—02

FIG. 1 is a view in side elevation of a compound lug wrench tool embodying my new design;

FIG. 2 is a bottom plan view thereof;

FIG. 3 is a fragmentary side elevational view of the right end thereof, taken from the opposite side;

FIG. 4 is a fragmentary top plan view thereof, taken on line 4—4;

FIG. 5 is a fragmentary front elevational view thereof, taken on line 5—5; and

FIG. 6 is a fragmentary rear elevational view thereof, taken on line 6—6.

I claim:

The ornamental design for a compound lug wrench tool, substantially as shown and described.
